UNITED STATES PATENT OFFICE.

CHARLES C. SUNDERLAND, OF TRENTON, NEW JERSEY, ASSIGNEE TO JOHN A. ROEBLING'S SONS COMPANY, A CORPORATION OF NEW JERSEY.

ROPE-THIMBLE.

1,121,806.

Specification of Letters Patent. Patented Dec. 15, 1914.

Application filed June 17, 1914. Serial No. 845,545.

To all whom it may concern:

Be it known that I, CHARLES C. SUNDERLAND, a citizen of the United States, residing at Trenton, county of Mercer, and State 5 of New Jersey, have invented certain new and useful Improvements in Rope-Thimbles, fully described and represented in the following specification and the accompanying drawings, forming a part of the same.

10 This invention relates to an improved thimble for use with wire rope, the especial object being to provide a thimble in which the rope shall be free to slide on the thimble under strain, to equalize the tension on two parts of the rope loop or for other purposes, while at the same time the thimble is of great strength and resistance to change in form, and simple and cheap of manufacture. The thimble is intended 15 especially for use in wire rope slings, but also is of general application as a rope thimble.

In the accompanying drawings, forming a part of this specification, there is shown a 20 rope thimble embodying all the features of the invention in their preferred form, and this construction will now be described in detail and the features forming the invention then specifically pointed out in the 25 claims.

30 In the drawings,—Figure 1 is a side view of the rope eye, partly in section, with the thimble in place. Fig. 2 is an edge view of the same; and Figs. 3, 4, 5 and 6 are 35 sections on, respectively, the lines 3—3, 4—4, 5—5 and 6—6, of Fig. 1.

Referring to the drawings, the thimble or eye piece, is formed in two sections A, A', divided centrally of the rope groove and secured together by rivets 10 through the 40 bodies of the two sections, so as to form the usual groove for receiving the rope X. At the inner end of the thimble, the parts A, A', are shaped to form overlapping studs 45 11, 12, between the ends of the rope groove, projecting in opposite directions from the respective parts. These ribs preferably are wedge shaped, as shown, so as to avoid looseness when forced together, and are provided with holes through which passes pin 50 13, by which the thimble is held in form and the two parts A, A', secured together at the inner end of the thimble, this pin 13 being secured by rivets 1 passing through 55 the pin and studs 11, 12. The two parts of

the thimble, also, are provided at their inner ends with ribs outside the rope groove, these ribs extending in opposite directions from the parts A, A', and overlapping so as to form a ring by which the rope is held in 60 place. These ribs preferably are wedge shaped for tightness, as shown, and are provided with holes through which pass pins 16 secured by rivets 1 to hold the ribs and thimble parts together, two pins 16 preferably being used on each side of the thimble, as shown.

In addition to the studs 11, 12, and overlapping ribs 14, 15, for holding the two parts of the thimble from slipping on each 70 other under the rope tension, the two parts A, A', preferably are provided with corresponding recesses and studs 17, 18, on opposite sides of the thimble, through which pass some of the rivets 10, so that the shoulders 75 on these engaging studs and recesses aid in strengthening the thimble against the tension caused by excessive strain on one part of the rope, and against flattening or elongation of the thimble.

The thimble may be used without any 80 means at the outer end of the thimble for holding the rope in the thimble groove, but preferably the two parts of the thimble A, A', will be provided with overlapping ears 85 19, for holding the rope in place, as usual in other thimbles.

What I claim is—

1. A rope thimble consisting of two parts, the line of division being longitudinally of 90 the rope groove, and having at its inner end overlapping studs projecting in opposite directions from the two parts of the thimble between the rope grooves, said studs being provided with openings in line, and fastening means passing through said openings for locking the studs together.

2. A rope thimble consisting of two parts, the line of division being longitudinally of 100 the rope groove, and having at its inner end overlapping studs projecting in opposite directions from the two parts of the thimble between the rope grooves, said studs being provided with openings in line, and overlapping ribs outside the rope groove extending in opposite directions from the two parts of the thimble and provided with openings in line, and fastening means passing through said openings for locking the 105 studs and ribs together.

3. A rope thimble consisting of two parts, the line of division being longitudinally of the rope groove, and having at its inner end overlapping wedge shaped studs projecting in opposite directions from the two parts of the thimble between the rope grooves, said studs being provided with openings in line, and fastening means passing through said openings for locking the studs together. 35
- 10 4. A rope thimble consisting of two parts, the line of division being longitudinally of the rope groove, and having at its inner end overlapping wedge shaped studs projecting in opposite directions from the two parts of the thimble between the rope grooves, said studs being provided with openings in line, and overlapping wedge shaped ribs outside the rope groove extending in opposite directions from the two parts of the thimble and 40 provided with openings in line, and fastening means passing through said openings for locking the studs and ribs together. 45
- 15 5. A rope thimble consisting of two parts, the line of division being longitudinally of the rope groove, and having at its inner end overlapping studs projecting in opposite directions from the two parts of the thimble between the rope grooves, said studs being provided with openings in line, and overlapping ribs outside the rope groove extending in opposite directions from the two parts of the thimble and 50 provided with openings in line, fastening means passing through said openings for locking the studs and ribs together. 55
- 20 6. A rope thimble consisting of two parts A, A', riveted together, each carrying part 40 of the rope groove, overlapping studs 11, 12 at the inner end of the thimble between the two parts of the rope groove having openings in line, locking pin 13 passing through said openings, overlapping ribs 14, 15 at the 45 inner end of the thimble outside the grooves having openings in line, and locking pin 16 passing through said openings. 60
- 25 7. A rope thimble consisting of two parts A, A', riveted together, each carrying part 50 of the rope groove, overlapping studs 11, 12 at the inner end of the thimble between the two parts of the rope groove having openings in line, locking pin 13 passing through said openings, overlapping ribs 14, 15 at the 55 inner end of the thimble outside the grooves having openings in line, locking pin 16 passing through said openings, and corresponding recesses and ribs 17, 18 on the two parts of the thimble between its ends. 60

In testimony whereof, I have hereunto set my hand, in the presence of two subscribing witnesses.

CHARLES C. SUNDERLAND.
